UNITED STATES PATENT OFFICE.

WILLIAM BAAKE, OF WEST HOBOKEN, NEW JERSEY,

TRousERS-SUPPORTER.

1,243,680.

Specification of Letters Patent. Patented Oct. 23, 1917.

Application filed May 1, 1917. Serial No. 165,788.

To all whom it may concern:

Be it known that I, WILLIAM BAAKE, a citizen of the United States of America, residing at West Hoboken, in the county of Hudson and State of New Jersey, have invented certain new and useful Improvements in Trouser-Supporters, of which the following is a specification.

This invention relates to garment supporters and more particularly to a device for supporting trousers.

It is well known that suspenders are objectionable to many persons. Where both trousers and vest are worn without suspenders the trousers frequently sag below the lower edge of the vest exposing the shirt between the vest and the waist band of the trousers. This is unsightly and consequently undesirable.

As this description proceeds it will be seen that the present invention provides a simple and inexpensive structure adapted to support the trousers from the vest, while permitting all necessary freedom of movement to the wearer.

Further objects and advantages of the invention will be set forth in the detailed description which now follows:

In the accompanying drawing,

Figure 1 is a perspective view of a device embodying the invention, illustrating the same in applied position.

Fig. 2 is a horizontal, sectional view through the upper clasp member.

Fig. 3 is a vertical, sectional view through the upper clasp member.

Fig. 4 is a front elevation of the lower clasp member.

Fig. 5 is a vertical, sectional view through the lower clasp member.

Like numerals designate corresponding parts in all of the figures of the drawing.

Referring to the drawing 5 designates a rubber of other elastic strand having an upper cap 6 and a lower cap 7 clipped thereupon. An upper clasp 8 is connected to the cap 6 and a lower clasp 9 is connected to the cap 7 and these clasps lie at right angles with respect to each other. In other words, the upper clasp 8 is adapted to act laterally so that it may engage the edge of the vest 10 adjacent the row of buttons 11 while the clasp 9 acts vertically to adapt it to engage the upper edge of the waist band of the trousers 12.

The structure of the lower clasp is clearly

illustrated in Figs. 4 and 5 from which it will be seen that the clasp comprises a U shaped body portion 13 which is cut away at 14 and the cut out portion is turned up to form an attaching ear 15. The ear 15 is provided with a transverse slot 16. The cap 7 carries a neck extension 17 having a right angularly disposed end 18 which terminates in a head 19. The head 19 is substantially as long, vertically considered, as the slot 16 is long. Since the slot 16 lies horizontally it follows that if the head 19 be turned to a horizontal position and passed through the slot 16 and then be turned to a normal or vertical position the cap 7 will be, consequently, held against disengagement from the ear 15.

This structure may be duplicated as the attaching means between the cap 6 and an ear 8', carried by the clasp 8. The clasps 8 and 9 are of a usual and well known type in which thumb levers 20 are pivoted at 21 and act to force one of the sides of the U shaped spring strips 22 toward the other of said sides said spring strips being provided with suitable teeth 23.

It is to be noted that the teeth in the clasp 9 are so disposed as to resist vertical movement of the clasp and that the same thing is true with respect to the teeth of the clasp 8. In other words, the teeth of the clasp 9 are so disposed as to resist movement of the clasp in a direction opposite to the movement that the clasp has when being applied but in the case of the clasp 8 the teeth are so placed as to resist movement of the clasp in a direction at right angles to the movement that the clasp has when being applied.

This novel correlation of the parts particularly adapts the structure for use in the relation shown. In other words, it provides a structure adapted to engage the edge of a vest and the waist band of a pair of trousers and to resist vertical movement of these parts with respect to each other. To this end the teeth of the clasp 8 are disposed horizontally with respect to each other and directed downwardly.

The provision of an elastic strand 5 permits the necessary limited, vertical movement between the clasps 8 and 9. This renders it possible for the wearer to have freedom of movement without danger of tearing the clothing. For example, it permits reaching and stretching upon the part of the wearer, the strand 5 yielding at such times,

while under normal condition the tension of this strand is such as to efficiently support the trousers with the waist band thereon materially above the lower edge of the vest.

5 By reason of the readily detachable connections between caps 6 and 7, upon the one hand, and the clasps 8 and 9, upon the other hand, it is not necessary to discard the entire structure if the strand 5 becomes worn.

10 Upon the contrary, by the mere provision of an additional strand 5 the structure may be rendered as good as when new.

15 It is to be understood that the invention is not limited to the precise construction set forth but that it includes within its purview whatever changes fairly come within the spirit of the appended claims.

Having described my invention what I claim is:—

20 1. A structure of the character described, comprising a strand, a clasp carried by the upper end thereof adapted to engage an edge lying in substantial parallelism with the strand, a plurality of downwardly directed teeth carried by the upwardly extending clasp, disposed in a line transverse to the line of pull upon the clasp and a

clasp connected directly to the lower end of said strand and disposed to engage an edge lying substantially at right angles to the first named edge and a plurality of teeth carried by the last named clasp disposed in a line also substantially transverse to the direction of pull to thereby resist movement of the clasp in a direction opposite to that movement that the clasp has when being applied.

2. A device of the character described, comprising an elastic strand having metallic caps at its upper and lower ends, right angular extensions carried by said caps and elongated heads on said extensions, a clasp at the upper end of the strand which lies and acts substantially at right angles to the direction of the strand, said clasp having an elongated slot at its lower side with which said right angular extension coacts, a second clasp disposed and acting in the line of said strand and having an upward extension with an elongated slot therein with which the lowermost right angular extension coacts.

In testimony whereof I affix my signature.
WILLIAM BAAKE.
